(57) **CLAIM**

The ornamental design for a can opener, as shown and described.

DESCRIPTION

FIG. 1 is a front right perspective view of a can opener according to an exemplary embodiment of the present invention.

FIG. 2 is a front elevational view of the can opener.

FIG. 3 is a back elevational view of the can opener.

FIG. 4 is a left side elevational view of the can opener.

FIG. 5 is a right side elevational view of the can opener.

FIG. 6 is a top plan view of the can opener; and,

FIG. 7 is a bottom plan view of the can opener.

The broken line showings throughout the views are for illustrative purposes only and form no part of the claimed design.
